PUMP

Samuel A. Mullins, Beaumont, Tex.

Application October 3, 1933, Serial No. 692,009
Renewed December 24, 1936

10 Claims. (Cl. 103—179)

This invention relates to improvements in pumps, and its objects are as follows:—

First, to provide a deep well pump in which the standing tube is provided with a helical ring first for the purpose of making a seal with the internal wall of the traveling tube, second for the purpose of aiding in working out sand and other foreign matter which may collect between the two tubes.

Second, to so arrange the foregoing helical ring and its ends that it will partake of a limited creeping motion in the helical groove of the standing tube for the purpose of preventing excessive binding between the ring and traveling tube on the up and down strokes.

Third, to provide the foregoing helical ring with end heads, which actually comprise a few substantially circular windings, for the purpose of permitting the limited creeping motion of the helical ring and the prevention of excessive friction between said ring and the wall of the traveling tube.

Fourth, to provide a deep well pump with a top latch, that is to say, an arrangement for latching the standing tube to the traveling tube at the topmost point between the two tubes, thereby making it possible to pull the standing tube even though the standing valve is sanded.

Fifth, to provide automatic compensating means to compensate for the natural tendency of the helical ring to expand due to the friction moment during reciprocation of the traveling tube, thereby guarding against binding between said ring and the wall of the traveling tube.

Sixth, to provide a helical ring for the purpose described, having its convolutions arranged on a very steep pitch, partly for the purpose of providing ample room between the convolutions for the reception and working out of foreign solid matter and partly for the purpose of producing a tortuous liquid passage which by virtue of its length insures a liquid seal.

Other objects and advantages will appear in the following specification, reference being had to the accompanying drawing in which,

Figure 1 is a partially sectional and elevational view of the lower part of a well, particularly illustrating the relationship of the improved pump.

Figure 2 is an enlarged view of the improved pump, particularly illustrating the helical ring and its compensating heads.

Figure 3 is a detail section taken on the line 3—3 of Figure 2.

The improvement disclosed herein is primarily

intended for use in connection with deep well pumps, although it is not confined to such use. It is the common practice in many oil fields to use the familiar composition cups in the pumping assemblage at the bottom of the well. It is generally always the case that the oil will be laden with sand and other solid foreign matter. This when coming into contact with the composition cups soon scores and cuts them up to such an extent that they lower in efficiency very rapidly.

There are in use devices of various sorts to entrap the sand and so guard the cups from premature destruction, but even these remedies are not always satisfactory. The instant invention is intended to do away with a sand trap as such, to replace composition cups, to overcome their limitations, to produce an effective liquid seal and at the same time to work out foreign solid matter which inevitably will find its way between the standing and traveling tubes.

Reference is made to the drawing. In Figure 1 the well casing is designated 1, the well tubing 2, the sucker rod 3, the traveling valve 4 and the standing valve 5. It is between the cages 6 and 7 of the two valves that the improved pump is connected in the pumping assemblage.

This pump comprises what is known as a traveling tube 8. This is the outer one of a pair of telescoped tubes which have a narrow working space 9 between them (Fig. 2), the inner and standing tube being designated 10. These tubes have a straight liquid course through them from the standing valve 5 to the traveling valve 4, with a freedom from obstruction of practically one hundred percent. An inward bevel at the top of the standing tube (dotted line, Fig. 2) tends to deflect any sand back into the liquid course.

The manner in which the standing tube is made stationary and from which it derives its name is this: Somewhere near the bottom of the well tubing 2 there is a sealing collar 11. This has a bevelled seat 12. The cage 1 has a correspondingly tapered seal ring 13 integrally affixed to it, for example by brazing. This seal ring is made of relatively soft metal, and its engagement with the seat 12 is maintained by the heavy liquid column always present within the well tubing 2. The seal ring 13 is in the nature of a base from which the standing tube 10 extends in fixed, upstanding relationship.

A helical groove 14 traverses the outside of the standing tube 10 for a distance of from one-fourth to one-third of its length beginning near the top. This groove communicates with an annular groove 15 at its top and a corresponding

annular groove 16 at its bottom. A helical ring 17 is fitted loosely in the groove 14. This so-called ring actually comprises flat stock. It might be called a rod, but by virtue of its specific 5 use the term ring has been adopted for its description.

The ring 17 consists of flexible springy material, and in the event of its being metal, as it 10 usually will be, it will be dissimilar to that of the traveling tube 8 with the inner wall of which contact is made as plainly shown in Figure 2.

Means to compensate for the limited elongated 15 creeping motion of which the ring 17 partakes in operation as will be brought out below, comprises end heads 18, 19 of a lesser depth than the 20 annular grooves 15 and 16 and having an outside diameter substantially the same as that of the standing tube 10. These are preferably continuations 25 at the ends of the ring 17 and comprise one or more complete turns to loosely occupy the annular grooves 15, 16. These grooves are deeper 30 than the heads 18 and 19 are thick in the axial direction of the pump, thereby providing ample room for a limited rectilinear motion of the heads.

Release openings 20 in the outer wall of the 35 standing tube 10 communicate with the groove 14 at its bottom (Fig. 3). These openings are for the purpose of enabling the escape of sand or 40 other foreign solid matter that may enter the groove 14 behind the ring 17.

The prevailing practice, for the purpose of 45 withdrawing the standing valve and tube, is to latch the traveling tube to the standing tube so as to make a temporary connection. When the sucker rod 3 is then pulled upon at the top, the standing valve and all of its related parts come with it. It is also the prevailing practice to 50 locate the latch arrangement between the traveling and standing tubes at the bottom near the standing valve.

This has the disadvantage of often preventing 55 the making of a connection by virtue of the standing valve having become sanded to a point above where the latch connection is to be made. One of the purposes of the present invention is to locate the latching arrangement at the top-most point between the tubes 8 and 10 so as to be so far away from the standing valve that the 60 likelihood of prevention of making a connection due to sanding is not apt to occur.

A pin 21 is affixed crosswise of the traveling 65 tube 8 near its top. The upper extremity of the standing valve 10 is provided with a double bayonet slot 22. Upon letting the traveling tube down far enough to enter the pin 21 into the groove 22 and then giving it a turn in the proper direction there will be an instant and easy latch connection locking the two tubes together for the purpose of withdrawal of the standing valve and tube.

The operation is readily understood. Bear in 70 mind that the standing tube 10 is the stationary member, and the traveling tube 8 the movable member. On a down stroke of the tube 8, liquid previously admitted to the tube 10 escapes into the well tubing 2 by an opening of the valve 4. On the up stroke of the tube 8 the opening of the standing valve 5 admits a new charge of liquid into the pump.

By virtue of the fact that the helical ring 17 is composed of springy material it follows that its 75 normal tendency is to expand against the inner wall of the traveling tube 8. This establishes a friction moment between the ring and the travel-

ing tube. If the ring were perfectly free it would traverse the groove 14 with a winding action during the reciprocations of the traveling tube. If one or both ends of the ring were anchored to prevent winding, the foregoing friction moment would cause the ring to buckle up or expand an excessive amount, setting up such severe binding actions between the ring and the traveling tube as to check the free movement of the latter and in all likelihood severely score the walls.

The remedy for these defects lies in the compensating means 18, 19. Consider the traveling tube 8 on its down stroke in the direction of arrow a (Fig. 2). The friction between the ring and the traveling tube moves the ring assemblage 15 downwardly so that the lower side of the head 18 is soon engaged at b with the bottom of the groove 15 with an appreciable frictional contact. This contact produces a temporary anchorage 20 for the head 18. The rest of the ring 17 is elongated, and the elongation is consumed or taken up by the tendency of the now freed head 19 to wind. It will be noticed that both the top and bottom of the head 19 are released from the top and bottom 25 of the groove 16 thereby enabling a free winding up of the surplus, so to speak, of the ring 17.

A similar action takes place on the up stroke 30 of the traveling tube 8. This time the tendency of the ring 17 is to move up in its groove 14. The top part of the bottom head 19 will be brought 35 into frictional engagement with the top part of the groove 16. The head 18 will be freed in the groove 15, taking a substantially central position. The upward crowding or elongation of the ring 17 is consumed by a slight winding up of the turns 40 of the head 18.

Thus it will be seen that the heads 18, 19 wind and unwind as becomes necessary to take care of the elongation of the ring 17 during the reciprocation of the traveling tube 8. Therefore they 45 comprise automatic compensators which prevent excessive friction between the ring and the traveling tube.

Inasmuch as the helical ring extends somewhere between one-fourth to one-third the length 45 of the standing tube 10 it follows that the helical liquid passage defined by the ring is of a substantial length. There is nothing to obstruct the free flow of liquid through this passage, it being noted that the heads 18, 19 are of lesser diameter 50 than the ring 17 because of their being substantially the same in diameter as the standing tube 10, but by virtue of its length and its continuous closing off by the ring 17 in the axial direction there is maintained what is known as a liquid 55 seal. The advantage of having the passage open is that any foreign matter entrapped in it will eventually be worked out at the bottom by the continuous declination of the helical ring. Any foreign matter working in behind the ring will 60 be released at the openings 20.

The foregoing description of the ring 17 and its functions obtains whether the helix 17 is right handed as shown, or left handed. It is contemplated that in some instances it will be 65 desirable to use a double arrangement of helical rings, that is to say two helixes (or more) entirely separate from each other and in tandem. In the event of this modification it would be a matter of choice whether or not to have the helical rings all right handed, or all left handed or a combination of the two.

In any case the ring 17 would function to seal and gradually eject foreign matter from the working space 9 whether this is between the rela- 75

tively stationary and movable members of a pump or some other contrivance which requires liquid sealing and the ejection of foreign matter as brought out.

5. I claim:—

1. The combination of a movable member and a stationary member telescoped therein there being a working space between said members, said stationary member having a helical groove, a resilient ring in the helical groove bridging the working space into frictional contact with the adjacent wall of the movable member, and means at the terminals of said ring capable of bodily winding and unwinding to continuously absorb elongations of the ring caused by said wall contact during reciprocations of the movable member.

2. The combination of a movable member and a stationary member telescoped therein there being a working space between said members, said stationary member having a helical groove, a resilient ring loosely mounted in said groove and bridging the working space into contact with the adjacent wall of the movable member, and means at the terminals of the ring capable of limited turning and endwise movement with respect to the stationary member for the absorption of the elongation of the ring caused by its wall contact during reciprocation of the movable member.

3. The combination of a movable member and a stationary member in telescoped relationship, said members having a working space therebetween, the stationary member having a helical groove terminating at its ends in annular grooves, a ring continuously loose in the helical groove during the reciprocation of the movable member and bridging the working space to make frictional contact with the adjacent wall of the movable member, and heads of lesser diameter than the ring at the terminals of the ring loosely occupying the annular grooves, said grooves being of materially greater axial depth than the thickness of said heads.

4. In a pump, a traveling tube and a standing tube telescoped therein there being a working space between said tubes, said standing tube having a helical groove terminating at its ends in annular grooves, a resilient ring in the helical groove bridging the working space into contact with the traveling tube, and heads of lesser diameter than the ring at the terminals of the ring, said heads turnably occupying the annular grooves and consisting of at least one convolution in continuation of said ring.

5. In a pump, a traveling tube and a standing tube telescoped therein there being a working space between said tubes, said standing tube having a helical groove terminating at its ends in annular grooves, a resilient ring in the helical groove bridging the working space into contact with the traveling tube, and heads of lesser diameter than the ring at the terminals of the ring, said heads turnably and axially slidably occupying the annular grooves and consisting of at least one convolution in continuation of said ring.

6. In a pump, a traveling tube and a standing

tube telescoped therein there being a working space between said tubes, said standing tube having a helical groove having its ends terminating in annular grooves, a resilient ring in the helical groove bridging the working space into contact with the traveling tube, and heads of lesser diameter than the ring at the terminals of the ring comprising contacting convolutions in continuation of the ring being loosely mounted in the annular grooves and of a materially lesser depth than said grooves. 5

7. In a pump, a traveling tube and a standing tube telescoped therein there being a working space between said tubes, said standing tube having a helical groove terminating at its ends in annular grooves and having at least one release opening in communication with the outer surface of the standing tube, a ring loosely mounted in the helical groove, bridging the working space into contact with the traveling tube and covering an end of the release opening, and at least one convolution of lesser diameter than the ring at each terminal of the ring loosely occupying the annular grooves. 15

8. In a pump, a traveling tube and a standing tube telescoped therein, said standing tube having a helical groove having each end terminating in an annular groove, a ring loosely mounted in the helical groove and subject to continuous axial creeping in alternately opposite directions by 25 virtue of frictional contact with the wall of the traveling tube during reciprocation, and heads at the terminals of the ring mounted in the annular grooves, said heads being of lesser diameter than the ring and of materially lesser depth than the 30 grooves.

9. In a pump, a traveling tube and a standing tube telescoped therein, said standing tube having a helical groove of steep pitch having each end terminating in an annular groove, a ring 40 loosely mounted in the helical groove and subject to creeping by virtue of frictional contact with the wall of the traveling tube, and heads at the terminals of the ring slidably mounted in the annular grooves, said heads being of lesser diameter than the ring and of materially lesser depth than the 45 grooves.

10. A pump comprising a stationary member and reciprocable member in telescoped and spaced relationship, the stationary member having a helical groove on its outer surface struck on a steep pitch to leave relatively wide surface expanses between the convolutions of the groove and the ends of the helical groove being enlarged, standing and traveling valves so combined 50 with the respective members as to take in and let out liquid during the reciprocation of the reciprocable member, a helical ring carried by the groove, contacting the reciprocable member to mark said surface expanses off into a tortuous 55 liquid passage and liquid seal, said ring being loose in the groove and capable of continuous creeping in the groove during reciprocation, and means at the ends of the ring going into the enlargements and limiting the creeping on the respective strokes of the reciprocation. 60
